CLAIM

The ornamental design for a position detector, as shown and described.

DESCRIPTION

FIG. 1 is a perspective front view of the position detector according to the present invention;

FIG. 2 is a front view of the position detector;

FIG. 3 is a rear view of the position detector;

FIG. 4 is a left side view of the position detector;

FIG. 5 is a right side view of the position detector;

FIG. 6 is a top view of the position detector; and,

FIG. 7 is a bottom view of the position detector.

The features shown in broken lines in the various Figures are for illustrating environmental structure and form no part of the claimed design.

(Continued)

More generally, the invention pertains to an ornamental design for an article of manufacture.
